PRESS-STITCHER SEWING MACHINE

William Heffron, Bronx, N. Y.

Application September 19, 1938, Serial No. 230,605

9 Claims. (Cl. 112—169)

This invention relates to new and useful improvements in a press-stitcher sewing machine, and relates particularly to uniqueness of design and operation thereof.

5 The invention has for an object the construction of a machine which is characterized by a U-shaped casing adapted to be engaged in one's hand with the arms of the casing extended horizontally with one's thumb or other finger at the top, and a specific sewing machine mechanism mounted within the casing adapted to be operated by manipulation of the thumb or other finger. The feature of the sewing machine resides in the fact that it may be held in one hand and operated 10 by said hand to sew materials.

The invention proposes to so arrange the parts of the sewing machine that material to be sewed may be engaged between the arms of the U-shaped casing.

20 Furthermore, the invention proposes the provision of a thumb wheel rotatively mounted within the casing and having a portion of its periphery extended from the casing and adapted to be turned to turn a fly wheel for starting the machine 25 in the right direction.

Another object of the invention resides in the provision of a rod eccentrically connected with the fly wheel of the machine, and springs associated with the rod in a certain manner to prevent the fly wheel from stopping at a "dead" 30 position.

Furthermore, new and useful features of this invention reside in the design and operation of the machine; meaning the general shape, compactability and portability, its method of operation by thumb or finger and handling with one hand; a novel folding down needle bar depressor, a new method of elevating and keeping elevated the pressure foot; crank assisting springs that 35 give permanent direction to the crank turning apparatus; a thumb wheel that permits of starting the mechanism or reversing the direction; a new method of holding the thread spool and giving tension variably adjusted to the thread thereon, 40 and a new type and arrangement of a thread pulling device.

45 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

50 Fig. 1 is a perspective view of a press-stitcher

sewing machine constructed according to this invention and shown in one's hand ready for operation.

Fig. 2 is a perspective view of the sewing machine per se viewed from a different angle with the 5 cover open.

Fig. 3 is an enlarged vertical sectional view of the sewing machine shown in Fig. 1.

Fig. 4 is a sectional view on the line 4—4 of 10 Fig. 3.

Fig. 5 is a fragmentary sectional view on the line 5—5 of Fig. 3.

Fig. 6 is a fragmentary perspective view of the top thread puller and adjacent parts.

Fig. 7 is a fragmentary detailed view of a portion of Fig. 3 showing particularly the top thread holding and tensioning means.

Fig. 8 is a fragmentary elevational view looking in the direction of the line 8—8 of Fig. 4.

Fig. 9 is an enlarged detailed view of a portion 20 of Fig. 4.

The press-stitcher sewing machine includes a substantially U-shaped casing 10 adapted to be engaged in one's hand with the arms 10^a and 10^b thereof extended horizontally and with one's thumb or other finger at the top. A needle bar means is mounted through the top arm 10^a of the casing and includes a vertically extended needle bar 11 for supporting a needle 12. This needle bar 11 has a concave head 13 against which one's thumb or other finger may be rested, as shown in Fig. 1, to depress the same. This concave head 13 is pivotally supported by a pintle 14 on the upper end of the needle bar 11. Stop elements 15 and 16 are formed respectively on 30 the concave head 13 and the needle bar 11 for limiting pivoting of these parts to a vertical position from a horizontally extended position. The arrangement is such that when the sewing machine is not used the concave head 13 may be 35 folded down to decrease the compass of the machine and it may repose in a cavity 10^c formed in the top of the casing 10, for this purpose.

The casing 10 is of hollow construction and is adapted to house the mechanism of the sewing 45 machine, as hereinafter more fully described. The casing is provided with a front cover 10^d which is supported by several hinges 17 to the body of the casing. This front cover may be opened as illustrated in Fig. 2 to expose the interior mechanism. Several clips 18^a are fixed on the cover and are engageable with the heads of screws 10^f on the casing 10 for holding the cover, resiliently closed.

A pressure foot means is mounted in the top 55

arm 18^a of the casing and includes a pressure foot 18 having a foot portion 18^a engageable against the top face of the bottom arm 18^b of the casing. The shank portion 18^b of the pressure foot extends upwards through the top arm 18^a of the casing. At an intermediate point a Z-shaped stud 19 projects from the side of the pressure foot. A spring 20 is coaxially mounted upon the pressure foot and acts against the top wall of the casing and the stud 19 for resiliently urging the pressure foot downwards. The stud 19 passes through a slot 21 formed in the casing 10. A head 22 fixedly engages upon the stud 19. The slot 21 has an offset top end, see Fig. 8, adapted to receive the stud 19 for holding the pressure foot in a raised position when required. To raise the pressure foot the head is forced upwards to compress the spring 20 and lift the pressure foot, and the head 22 is moved laterally to engage the stud in the offset portion of the slot and so hold the pressure foot in a raised position.

A cloth feeder means is mounted in the bottom arm of the casing and is extendible through the top face thereof to be cooperative with the pressure foot. This cloth feeder means includes a toothed cloth feeder bar 23 arranged immediately below the inner face of the top wall of the arm 18^b of the casing and engageable through openings 24 in this top wall. The toothed member 23 is mounted on a flat body 25 which is slidably supported in a particular manner by a screw 25^a mounted on a block 48 and engaging a vertical slot 25^b formed in the body 25, to permit the body 25 to pivot as well as slide vertically. A cam 26 is fixed on a shaft 31 rotative through the block 48. This cam 26 engages an opening 27 in the flat body 25. This opening 27 is of a width wider than the cam. The arrangement is such that as the shaft 31 turns, the cam 26 working in the opening 27 will pivot the frame body 25 about the screw 25^a and simultaneously raise and lower the flat body to move the toothed member 23 through a motion for feeding the cloth forward. The distance of advance of the feeders may be controlled by an adjustment screw 28 which threadedly engages through a side wall of the casing 10 and which limits lateral pivoting of the flat body 25. A spring 29 is mounted in the casing 10 and acts against the side of the flat body 25 which is opposite the screw 28. This spring 29 serves to hold the flat body 25 against the cam 26. When the screw 28 is turned further inwards it will limit the possible pivoting of the flat body 25 laterally. It should be noted that the cam 26 will then merely idle through a portion of the opening 27. In this manner the length of the stitch of the sewing machine may be controlled.

The needle bar 11 is slidably mounted through the top arm 18^a of the casing, and intermediate of its ends, within the compass of the top arm, a pintle 33 pivotally connects a lever 34 with a portion of the needle bar. This lever 34 is pivotally mounted intermediate of its ends by a pintle 35 upon a bracket 36 which is stationarily mounted within the casing. The rear end of the lever 34 is formed with a ball joint 38 connecting it with a rod 37 eccentrically pivotally connected by a ball joint 38 upon a fly wheel 39. This fly wheel is fixed on the shaft 31. The shaft 31 is rotatively supported in a block 48 fixedly mounted within the casing. The arrangement is such that when the fly wheel 39 is started rotating it is an easy matter to press down with the thumb or other finger on the head 13 of the needle

bar and add a turning torque to the fly wheel. When the eccentric rod 37 reaches the top of its stroke, pressure is released from the thumb head 13 so that the momentum of the turning parts and a spring 37^a lifts the needle bar 11 to its top position. The spring 37^a is coaxial on the bar 11 and acts between a pin 37^b on the rod and a portion of the casing 10. Additional energy may now be applied to the turning mechanism by pressing down with the thumb or finger on the head 13.

An arrangement is provided for preventing the eccentric rod 37 from stopping at a "dead" point. This means includes a pair of springs 41, 42 arranged on opposite sides of the vertical central line of the rod 37. Each of these springs is fixedly mounted at one of its ends upon the wall of the casing 10. The spring 41 acts against the rod 37 when the rod is in its top position. The spring 42 acts against the rod 37 when it is in its bottom position. These springs tend to push the rod 37 past the "dead" center at the top and at the bottom of the stroke.

A thumb wheel mechanism is provided for starting the fly wheel 39 rotating in the proper direction. This thumb wheel mechanism includes a thumb wheel 43 rotatively mounted upon a shaft 44 supported by the block 48. A portion of the periphery of the thumb wheel 43 projects through an opening 45 in a recessed area 10^c in the bottom wall of the casing 10 so that it may be turned by one's thumb. The periphery of the thumb wheel 43 is formed with gear teeth which mesh with a pinion 46 fixed upon the shaft 31. The shaft 44 is pivotally mounted in the block 48.

A pintle 44^a serves to pivotally support the inner end of the shaft 44 within a cavity 48^a formed in the block 48. A spring 48 has a portion coaxially arranged on the pintle 44^a and 48 has one of its ends engaging the shaft 44 and its other end engaging a lug 47 mounted upon the casing 10. The spring 48 acts to normally pivot the shaft 44 against the lug 47 so that the gear teeth upon the thumb wheel 43 are out of mesh with the teeth of the pinion 46. When one places his thumb against the projecting end of the thumb wheel 43, he will oppose the action of the spring 48 and engage the gear teeth of the thumb wheel 43 with the pinion 46. Rotations of the thumb wheel will then be transmitted to the pinion 46 for starting the machine in a direction desired. When the machine is not in use, and when the machine is normally running, the thumb wheel 43 will be in an idle position. Because of the cavity 10^c in the casing 10, at no time will the thumb wheel 43 project outside of the side wall of the casing.

A spindle 51 is mounted inside upon a wall of the casing 10 and is adapted to support a spool 60 of thread 52. The spindle 51 is of oval shape in transverse cross section as indicated in Fig. 7. A flat spring 51 is riveted upon the inner end of the spindle 51 and will be held non-rotative because of the shape of the spindle. The spool 52 is free to turn on the spindle. The spindle 51 has a reduced end 51^a which projects through the wall of the casing 10. An adjustment nut 53 is threadedly mounted on the end 51^a and bears against the wall of the casing 10. The spring 51 bears against one face of the spool 52. The arrangement is such that the nut 53 may be turned to control the pressure of the spring 51 against the side of the spool 52. In this manner the tension of the thread 52 may be controlled.

5 The thread 52' from the spool of thread is threaded through the needle 12 secured on the lower end of the needle bar by a thumb screw 56. This needle 12 is adapted to engage through an opening in the pressure foot and an opening in the cloth feeder means so as to be capable of forming a loop within the bottom arm of the casing. A looper wheel 57 is mounted upon the shaft 31 and is formed with a hook portion 10 adapted to catch the loop of the thread.

15 This looper wheel 57 is adapted to form a chain stitch. While this particular type of machine has been disclosed it should be borne in mind that by a substitution of a conventional bobbin and associated looper wheel it is possible to convert the stitching machine to one making a lock stitch. Since such variation will readily be known to those skilled in the art further amplification on this point will not be given in this specification.

20 A means is provided for pulling the top thread tight after the loop has been operated on by the looper 57. This means includes a lever 61 formed with an eye portion 61^a at one end through which the thread 52' engages. The middle of the lever 25 61 is pivotally supported by a pintle 62 mounted in the bracket 36.

25 The rear end of the lever 61 engages the under-side of the lever 34. The parts are so proportioned that the lever 61 will act to pull the thread 30 52' tight at the correct instant. The thread 52' extends from the spool 52 through a stationary guide element 52^b mounted upon the inner wall of the casing, then continues out through an opening 52^a formed in the wall of the casing, then continues through the eye portion 61^a, and finally through the eye of the needle 12. The front end of the lever 61 passes through an opening 61^b formed in the bottom wall of the arm 10^a of the casing 10.

40 A means is also provided for tensioning the spool 52. This means includes a tension spring 71 engaging against a face of the spool 52. This spring 71 is mounted on the spindle 51 as previously explained. The spool 52 may be tensioned 45 by the proper operation of the nut 53.

The operation of the device is as follows:

45 The press-stitcher sewing machine is held in one's hand as illustrated in Fig. 1. Cloth material to be sewn is placed in between the arms 10^a and 10^b of the casing beneath the pressure foot 18. The pressure foot 18 may be momentarily raised to permit the proper engagement of the cloth material in position. The thumb wheel 43 is then turned in the proper direction to start the sewing machine. The power is then applied by 50 pressing down with the thumb or finger on the needle bar 11 and reciprocating this bar as previously described. This reciprocative motion operates the sewing machine by driving the shaft 31. Rotation of the shaft 31 operates the looper wheel 57 and the feeder mechanism, and the 55 thread puller lever 61. The sewing machine is now operating.

60 While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

75 1. A press-stitcher sewing machine, comprising a substantially U-shaped casing adapted to be

engaged in one's hand with the arms thereof extended horizontally and one's thumb or other finger at the top, cloth feeder means mounted in the bottom arm of said casing and extendable through the top face thereof, pressure foot means 5 mounted on the top arm of said casing and acting against said cloth feeder means, a needle bar means mounted through the top arm of said casing and supporting a needle engageable through apertures in the pressure foot and feeder and having an upwardly extending portion, a member 10 mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted 15 on said shaft in a position to be cooperative with said needle, a flywheel mounted on the rear end of said shaft, an eccentric rod connected with said flywheel, a pivotally mounted lever connected with said rod and with said needle bar, thread holding and guiding means, and a thread puller 20 synchronized with said needle bar.

25 2. A press-stitcher sewing machine, comprising a substantially U-shaped casing adapted to be engaged in one's hand with the arms thereof extended horizontally and one's thumb or other finger at the top, an adjustable cloth feeder means mounted in the bottom arm of said casing and extendable through the top face thereof, pressure foot means mounted on the top arm of said casing and acting against said cloth feeder means, a needle bar means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, resilient means for moving said rod out of a "dead" position, a pivotally mounted lever connected with said rod and with said needle bar, thread holding and guiding means including a spool and a tensioning spring for the spool, and a thread puller 30 synchronized with said needle bar, said casing having an open side, and a cover for closing said 35 side.

3. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting against said cloth feeder means, a needle bar 40 means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, resilient means for moving said rod out of a "dead" position, a pivotally mounted lever connected with said rod and with said needle bar, thread holding and guiding means including a spool and a tensioning spring for the spool, and a thread puller 45 synchronized with said needle bar, said casing having an open side, and a cover for closing said 50 side.

4. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting against said cloth feeder means, a needle bar 55 means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, resilient means for moving said rod out of a "dead" position, a pivotally mounted lever connected with said rod and with said needle bar, thread holding and guiding means including a spool and a tensioning spring for the spool, and a thread puller 60 synchronized with said needle bar, said casing having an open side, and a cover for closing said 65 side.

5. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting against said cloth feeder means, a needle bar 70 means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, resilient means for moving said rod out of a "dead" position, a pivotally mounted lever connected with said rod and with said needle bar, thread holding and guiding means including a spool and a tensioning spring for the spool, and a thread puller 75 synchronized with said needle bar, said casing having an open side, and a cover for closing said side.

- 5 tending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, a pivotally mounted lever connected with said rod and with said needle bar, thread holding and guiding means, and a thread 10 puller synchronized with said needle bar, comprising a thread puller lever pivotally mounted and having a loop through which the thread passes and one end of said thread puller lever being in contact with said first named lever to be moved thereby.

15 6. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting 20 against said cloth feeder means, a needle bar means mounted through the top arm of said casing and supporting a needle engageable through apertures in the pressure foot and feeder and having an upwardly extending portion, a member 25 mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted 30 on said shaft in a position to be cooperative with said needle, a flywheel mounted on the rear end of said shaft, an eccentric rod connected with said flywheel, a pivotally mounted lever connected with said rod and with said needle bar, thread holding and guiding means, a thread 35 puller synchronized with said shaft, and a thumb wheel rotatively and pivotally supported, geared with said flywheel and movable to a position out of connection therewith.

40 7. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting 45 against said cloth feeder means, a needle bar means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal 50 position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, a pivotally mounted lever connected with said rod and with said needle bar, thread holding and guiding means, a thread 55 puller synchronized with said shaft, and a thumb wheel rotatively and pivotally supported, geared with said flywheel and movable to a position out of connection therewith.

55 8. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting against said cloth feeder means, a needle bar means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel 60 mounted on said shaft in a position to be cooperative with said needle, a flywheel mounted on the rear end of said shaft, an eccentric rod connected with said flywheel, a pivotally mounted lever connected with said rod and with said needle bar, thread holding and guiding means, a thread 65 puller synchronized with said shaft, and a thumb wheel rotatively and pivotally supported, geared with said flywheel and movable to a position out of connection therewith.

70 9. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting against said cloth feeder means, a needle bar means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel 75 mounted on said shaft in a position to be cooperative with said needle, a flywheel mounted on the rear end of said shaft, an eccentric rod connected with said flywheel, a pivotally mounted lever connected with said rod and with said needle bar, thread holding and guiding means, a thread puller synchronized with said shaft, and a thumb wheel rotatively and pivotally supported and connected with said flywheel and movable to a position out of connection therewith.

- to a position out of connection therewith, the periphery of said thumb wheel being formed with gear teeth, a pinion mounted coaxial with said flywheel and meshing with said gear teeth, and said thumb wheel being movable to disengage the mesh of the gear teeth with said pinion, 5
5. A press-stitcher sewing machine, comprising a substantially U-shaped casing adapted to be engaged in one's hand with the arms thereof extended horizontally and one's thumb or other finger at the top, cloth feeder means mounted in the bottom arm of said casing and extendable through the top face thereof, pressure foot means mounted on the top arm of said casing and acting against said cloth feeder means, a needle bar means mounted through the top arm of said casing and supporting a needle engageable through apertures in the pressure foot and feeder and having an upwardly extending portion, a member mounted upon the end of said upwardly extending portion and upon which one's thumb may be engaged for urging said needle bar downwards to engage said needle through the apertures in said pressure foot and feeder, a resilient means for returning said needle bar to its normal position when the pressure on said member is released, a block mounted in the bottom arm, a shaft rotative through said block, a looper wheel mounted on said shaft in a position to be cooperative with said needle, a flywheel mounted on the rear end of said shaft, an eccentric rod connected with said flywheel, a pivotally mounted lever connected with said rod and with said needle bar, thread holding and guiding means, a thread puller synchronized with said shaft, and a thumb wheel rotatively and pivotally supported and connected with said flywheel and movable to a position out of connection therewith, the periphery of said thumb wheel being formed with gear teeth, a pin- 40
- ion mounted coaxial with said flywheel and meshing with said gear teeth, and said thumb wheel being movable to disengage the mesh of the gear teeth with said pinion, said thumb wheel being mounted upon a pivotally supported shaft, and resilient means for urging said shaft to dis- connect said gears. 5
9. A press-stitcher sewing machine, comprising a substantially U-shaped casing adapted to be engaged in one's hand with the arms thereof ex- 10 tended horizontally and one's thumb or other finger at the top, cloth feeder means mounted in the bottom arm of said casing and extendable through the top face thereof, pressure foot means mounted on the top arm of said casing and act- 15 ing against said cloth feeder means, a needle bar means mounted through the top arm of said cas- ing and supporting a needle engageable through apertures in the pressure foot and feeder and having an upwardly extending portion, a mem- 20 ber mounted upon the end of said upwardly ex- tends portion and upon which one's thumb may be engaged for urging said needle bar down- 25 wards to engage said needle through the ap- 30 pertures in said pressure foot and feeder, a resil- 35 ient means for returning said needle bar to its normal position when the pressure on said member is re- leased, a block mounted in the bottom arm, a shaft rotative through said block, a looper wheel mounted on said shaft in a position to be co- operative with said needle, a flywheel mounted on the rear end of said shaft, an eccentric rod connected with said flywheel, a pivotally mounted lever connected with said rod and with said needle bar, thread holding and guiding means comprising a holder for a spool of thread slidably mounted within said casing, and a tension device for controlling the unwinding of said spool. 40

WILLIAM HEFFRON.
